TROUSER-CREASING APPARATUS

Louis F. Clements, Los Angeles, Calif.

Application May 29, 1944, Serial No. 537,785

5 Claims. (Cl. 38—70)

1

This invention relates to mechanisms for creasing men's trousers, women's slacks and similar wearing apparel and is especially adapted to devices for applying pressure for appreciable intervals of time as the sole creasing agency, whereby application of heat, and usually of moisture, is avoided.

The principal object of the invention is to produce an especially simple, effective and cheap construction for the purpose.

Although trouser-creasing appliances of the pressure type have been known for many years, they have had various disadvantages. For example, some of the structures used heretofore have been made of steel and have been too heavy to be acceptable to the trade. Others have been unduly complicated and as a result have been either too expensive or too awkward to operate, or both, and likewise have not been acceptable. As a result of these and other objections, trouser creasers of the nature described have never attained the popularity to which they are reasonably entitled, although there is a wide potential market for a structure which would have general appeal. Modernly, trouser creasing is commonly a function of the tailor or of specialized pressing services, but much of this custom is a result of the convenience of employing such services in the absence of simple means for home use by individuals. Even though trouser-creasing appliances of the present type cannot meet all requirements, nevertheless, creases which have become slightly affected by a day's wear may be readily restored by a slight stretching and straightening of the garment to restore normal shape and the application of pressure for an appreciable interval of time, for example overnight, to restore the original sharp creases. Such a function of continually maintaining sharp, straight creases in trousers is one that can scarcely be performed for the ordinary individual by pressing services because of the required frequency of operation.

A further object of the invention, therefore, is to provide such a structure that will appeal to individuals because of simplicity of operation and because of such modest cost that they may possess as many as convenient to use.

I have discovered a form of construction for trouser creasing devices which renders the apparatus simple to manufacture and easy to operate by the user in his home, and of such cheapness as to enable an ordinary individual to provide one for each pair of trousers which he owns.

Other objects and features of the invention are found in the employment of long strips of rigid

2

material of relatively soft or fibrous nature as compared with metal, and of light weight as compared with metal, for example wood, wherein two spaced units or body members are employed for creasing opposite edges of trouser legs, each unit comprising a flat rabbeted body member to an edge of which adjacent to the rabbet a cooperating elongated presser plate is hinged, preferably by means of a special fabric hinge construction.

10 In a preferred form, a plurality of locking bars is employed, one end of each of which is movably connected with one of the rabbeted members and the other end of each of which is adapted to connect detachably with the other rabbeted member 15 to bind the presser plates in clamping position whereby to press the edges of trouser legs between the rabbeted members and the presser plates. According to a preferred construction, pairs of spacing arms are frictionally pivoted together 20 and at opposite ends are frictionally secured to the faces of the rabbeted members opposite from the presser plates. A further preference requires that each pair of spacing arms be so set as to tend to shift or cant the body members with respect 25 to each other when the locking bars are in operative position, whereby to yield a tensioning effect upon the locking bars and also to increase the clamping pressure of the locking bars upon the presser plates.

30 Other objects and features of the present invention will be apparent to those skilled in the art upon reference to the following specification and accompanying drawing, wherein certain embodiments of the present invention are disclosed for 35 purpose of illustration.

In the accompanying drawing wherein one embodiment of this invention is disclosed by way of illustration,

Fig. 1 is a plan view showing the parts of the 40 present structure in operative relation holding a pair of trousers in creasing position;

Fig. 2 is a cross-section taken approximately from the line 2—2 of Fig. 1;

Fig. 3 is a similar cross-section, the two spaced 45 body members, however, not being connected in operative relation, whereby to show their non-aligned position under such conditions;

Fig. 4 is a cross-sectional detail taken on the 50 line 4—4 of Fig. 1;

Fig. 5 is a similar cross-section detail showing the presser plate in non-engaging position;

Fig. 6 is a cross-sectional detail, as indicated 55 by the line 6—6 of Fig. 1, the presser plate, however, being raised into non-engaging position:

Fig. 7 is a side elevational detail, as indicated by the line 7—7 of Fig. 1; and

Fig. 8 is a side elevational detail, as indicated by the line 8—8 of Fig. 1.

In the form of construction shown in the drawing, a pair of spaced elongated body members 10 is provided, these members being adapted to receive the opposite creased edges of trouser legs and being formed of single lengths of material, each of which is sufficiently long to engage the creased portions throughout their full extent. Each member 10 comprises a relatively wide base plate 12 at one side of which an upstanding side rail or border 14 is provided by means of rigid connection therewith as by being integrally formed. Such a structure of the body members 10 is the result of a rabbet 15 produced either by a rabbeting tool where wood or similar fibrous material is employed, or by molding where plastic or a kindred material is used. For the purpose of binding the edge of a trouser leg upon the base plate 12 of each member 10, a hinged flap or presser plate 16 is disposed in the rabbet 15 when in operative position, the presser plate 16 corresponding approximately in size and shape with the size and shape of the rabbet 15, and being of a length equal to the length of the body member 10. The outer edge of the inner side of each presser plate 16 is hingedly connected with the adjacent edge of the contiguous wall of the upstanding rail 14, such hinge preferably being a fabric hinge 18, as hereinafter described.

Against the rear face of each base plate 12, that is the outer face opposite from the corresponding presser plate 16, one arm of each of a pair of spacing arms 20 is positioned, each pair of arms 20 being pivotally bound together as by a rivet 22 to form a friction joint, and the opposite end of each arm 20 being frictionally secured to the remote edge of the corresponding body member 10 opposite the respective rail 14, washers 23 and wood screws 24, or the like, being employed for the purpose. The arms 20, which are formed of wood or other material of which the body members 10 are formed, have appreciable thickness, as shown, which results in an offset arrangement of the two arms 20 of each pair with respect to the two body members 10. The arms 20 cooperate with a plurality of locking bars 25 carried on the opposite face of the structure to clamp the presser plates 16 in creasing position. One end of each of these locking bars 25 is pivotally mounted, as by means of a screw 26 and a washer 27, upon the forward face of one of the rails 14, and each locking bar 25 is of such length that it will span the structure when the spacing arms 20 are in their position of maximum extension. The free ends of the locking bars 25 are adapted to engage within retainers 28 shown as carried on the rail 14 of the body member 10 opposite from that carrying the pivot screws 26. The retainers 28 illustrated are in the form of locking jaws or hooks undercut on an incline at 30 to receive the corresponding edges of locking bars 25 whereby to wedge the bars 25 into locking position against the bases 32 of the hooks. The bases 32 serve to space the hooks 28 from the faces of the rails 14, the walls adjacent the rails 14 being bound to the rails by means of a plurality of screws 34 passing through each of said bases 32 into the corresponding rail 14. Thus, when the presser plates or flaps 16 are moved into their clamping positions, as shown in Fig. 2, and the locking bars 25 are swung on their pivots 26 into engagement with the inclined faces 30 of the hooks 28,

this action tends to establish a biased relationship which produces a binding effect upon the free edges of the presser plates 16 and causes the rear walls of the base plates 12 to move into the same plane. This results in a limited amount of flexure of the spacing arms 20, somewhat as indicated in Fig. 2, and at the same time causes some flexure of the locking bars 25, especially when trousers are being creased, somewhat as indicated in broken lines in Fig. 2. The general result is a firmer engagement of the swinging ends of the locking bars 25 with the inclined faces 30 of the hooks 28 and an increased clamping action of the presser plates or flaps 16 along the fabric held against the base plates 12.

For the purpose of hanging the creasing device, one end, which may be termed the "upper" end, of each body member 10 is provided on the rear face with a hook 35 similar to the hooks 28. These hooks 35 may be placed over the transverse bar of a conventional wire coat hanger 36 or wooden coat hanger, or may be caught on the edge of a shelf or similar support.

With respect to the hinge structure indicated at 18, while it might be sufficient for some uses to employ other forms of hinges to secure the presser plates 16, a preferred construction is a fabric hinge, such as illustrated in Fig. 6, wherein a long fabric strip 40 runs the full length of each body member 10 and its flap or presser plate 16. The strip 40 in each instance covers the inner face 42 and the inner edge 43 of the presser plate 16, and also covers the inner side wall 44 of the rail 14 and the upper face 45 of the base plate 12. Thus, the strip 40 at an intermediate point forms a bend 46 which acts as a hinge, the portions which are secured to the faces 42 and 45 acting also as friction elements for fabric clamped between the plates 12 and 16.

Also, a plurality of spaced auxiliary fabric hinges 48 is employed. Each of these auxiliary hinges is in the form of a fabric strip 50 secured at least to the outer face 51 of the presser plate 16 and to the outer face of the rail 14. Preferably, one end 52 of each hinge strip 50 passes around the outer side of the presser plate 16 and is secured on the inner face 42 under the adjacent portion of the longitudinally extending hinge strip 40, as seen in Figs. 4 and 5. Similarly, the opposite end 53 of each hinge strip 50 preferably extends around the body member 10, crossing its under face opposite from its upper face 45, and is secured to the upper face 45 under the adjacent portion of the hinge strip 40. Desirably, one end 52 follows the hinge strip 40 along the inner edge 43 of the presser plate 16 and the inner side wall 44 of the rail 14, thereby reinforcing the hinge 46, and continues thence onto the face 45 where the extremities of the two ends 52 and 53 may abut as at 56 under the adjacent portion of the strip 40.

One of the functions of the hinges 48 is to resist the lateral movement of the presser plate 16 when being lowered to closed position, whereby to resist separation of the adjacent strip 40 from the corresponding side wall 44 of the adjacent side rail 14. Similarly, one of the functions of each hinge strip 40, when the presser plate 16 is open, is to resist outward motion of the presser plate 16 and avoid pulling of the hinge strips 50 from the outer face of the corresponding rail 14.

The hinge strips 40 and 50 may be of any appropriate fabric suitably cemented to the body members 10 and the presser plate 16. For ex-

ample, for a superior construction, an adhesive cloth tape provided with cementing material which is waterproof and adequately adherent to the wood, or plastic material, or other substance of which the parts 18 and 16 are made, may be employed. For cheaper construction, tough, heavy paper strips may be used and secured by water-proof cements or glues.

Operation

In using the creasing apparatus of this invention, the locking arms 25 are disconnected from their retaining hooks 28 and are moved about their pivots at 26 to a position in which they clear the adjacent presser plate 16. When in such relation, the presser plate 16 may be raised to a position, such as indicated in Figs. 5 and 6, and, similarly, the presser plate 16 of the opposite member 10 may be raised. The creased edges at one side of both legs of a pair of trousers are then laid upon the upper face of one base plate 12, and the presser plate 16 is folded down upon the fabric to a position approximately as indicated in Figs. 2 and 3. The dimensioning may be such as to allow a limited amount of space between the presser plate 16 and the base plate 12 to avoid overcrowding. When the edges at one side of the trouser legs have been properly placed, the opposite edges of the trouser legs are similarly placed on the other base plate 12 and the corresponding presser plate 16 lowered into its clamping position. Preferably, the trouser edges are first placed in that body member carrying the locking bars 25, so that, by swinging the locking bars 25 part away across the respective presser plate 16, the latter may be lightly retained in clamping position while the opposite edges of the trouser legs are being placed in the other body member 10. The locking bars 25 are then swung into engagement with their respective hooks 28. Hems or cuffs are preferably disposed beyond the upper ends of the clamping members in order to relieve the apparatus of the corresponding extra thicknesses of fabric which would otherwise interfere with the clamping operation. The apparatus is then expanded by reason of the pivotal movement of the arms 20 of each pair about their pivot points 22, whereby the trouser legs are stretched into shape. Having accomplished proper shaping and stretching, the free ends of the locked bars 25 are pressed as tightly as possible into engagement behind the hooks 28. By hanging the supporting hooks 35 carried on the back walls of the upper ends of the members 10 over a conventional coat hanger 36, the creasing apparatus with the trousers carried therein may be suspended from any suitable support.

Normally, several hours of pressure are sufficient to provide sharp creases. By reason of the elongated hinges formed at 46 by the fabric strips 40, firm engagement with the edges of the trouser legs is produced throughout the lengths of the body members 10. Commonly, when the presser plates 16 are moved down into clamping position, there is some tendency for the plates 16 to assume a slightly angular position with respect to the base plates 12. This condition, taken in connection with the movement of the one body member 10 from the position shown in Fig. 3 into parallelism with the other body member 10 when the locking bars 25 are moved into their locking positions behind the retaining hooks 28, results in a limited amount of flexure of the spacing arms 20, as shown in Fig. 2, and also of the lock-

ing arms 25, as indicated in broken lines in Fig. 2. However, the flexure of the locking bars 25, shown in broken lines, is not so pronounced when edges of trouser legs are not clamped in place.

- 5 When the pressing apparatus is to be stored, the locking bars 25 are swung toward each other so as to overlie portions of the corresponding member 10, the extremities of the two bars lying alongside each other. The two members 10 are then moved into collapsed position, the two pairs of spacing arms 20 likewise collapsing, so that the whole structure is arranged in compact form requiring no more space than the width of the two members 10 lying in parallelism with one another. In this collapsed condition, the apparatus requires only a limited amount of space for packing and transport.

It is to be understood that the form of the invention here disclosed is merely illustrative of the generic invention sought to be protected, and that, since many modifications will be apparent to those skilled in the art, all such variations as fall within the scope of the appended claims are intended to be covered thereby.

25 I claim as my invention:

1. In combination in a trouser-creasing mechanism: a pair of spaced elongated body members, each of said body members being provided with a longitudinally extending rabbet forming an upstanding outer rail and the rabbets of said body members being directed toward each other; means adjustably connecting said body members in spaced relation; presser plates disposed in the rabbets in said body members; means hingedly connecting said presser plates to adjacent edges of said rails, such hinge means comprising a plurality of fabric hinges connecting each presser plate with its body member, each hinge comprising a fabric strip extending around portions of the corresponding presser plate and around portions of the corresponding body member, portions of each strip lying closely adjacent one another at the point of hinged connection between said plate and said body member, and a second fabric strip extending substantially the full length of each presser plate and body member and being secured to the respective presser plate and body member and being folded along the line of hinged connection to form a hinge construction; and locking means mounted upon each of said rails and spanning the space between said body members in engaging relation with said presser plates to clamp said plates against said body members.
2. In combination in a creasing device: an elongated body member having a rabbet extending longitudinally thereof and providing an upstanding side rail, a side wall of said rabbet and a presser face; a presser plate disposed in said rabbet having a presser face opposing the first mentioned presser face and a side wall opposing the first mentioned side wall; and a fabric hinge comprising two fabric strips spanning a joint between the edge of the rail adjacent said rabbet and the adjacent edge of said presser plate, one of said strips being attached to outer faces of said rail and said presser plate, and the other of said strips being attached to said opposing side walls of said rabbet and said presser plate.
3. In combination in a trouser-creasing mechanism: a pair of elongated spaced body members, each body member having a longitudinally extending rabbet, said rabbets forming upstanding side rails on said body members and said rabbets being directed toward each other; a pair of spac-

ing arms of appreciable thickness pivotally secured together at one end in frictional relationship, the opposite end of each arm being bound against the face of the respective body member opposite its rabbet, and said opposite end of each arm being frictionally secured to the respective body member opposite the respective rail whereby said members assume positions out of a common plane; presser plates movably mounted in said rabbets and adapted to clamp opposite edges of a trouser leg against said body members; a locking bar movably connected with said side rails and adapted to engage said presser plates; and means adapted to bind said locking bar against said side rails and said presser plates and to flex said spacing arms and move said body members toward a common plane.

4. In combination in a trouser-creasing mechanism: an elongated body member provided with a longitudinally extending rabbet forming an up-standing outer rail; a presser plate disposed in said rabbet; locking means carried by said rail and adapted to engage said presser plate to clamp the latter against said body member; and hinge means connecting said presser plate to the adjacent edge of said rail, said hinge means comprising a plurality of fabric hinges, each hinge comprising a fabric length extending along portions of the presser plate and along portions of said rail, portions of such lengths lying closely adjacent one another at the point of hinge connection between said presser plate and said rail, each hinge having a fabric length extending entirely around said presser plate and entirely around said body member.

5. In combination in a trouser-creasing mechanism: an elongated body member provided with a longitudinally extending rabbet forming an up-standing outer rail; a presser plate disposed in said rabbet; locking means carried by said rail and adapted to engage said presser plate to clamp the latter against said body member; and hinge means connecting said presser plate to the adjacent edge of said rail, said hinge means comprising fabric lengths spanning a joint between the edge of the rail adjacent said rabbet and the adjacent outer edge of said presser plate, one of said fabric lengths being attached to an outer face of said rail and an outer face of said presser plate, and another of said fabric lengths being attached to opposing side walls of said rabbet and said presser plate and folded along the line of the hinge connection, said presser plate and said rabbet providing opposing presser faces and said other of said fabric lengths extending along said presser faces and providing opposed friction elements.
